WATER HEATER CONTROL SYSTEM

Clark M. Osterheld, Stoughton, Wis., assignor to
McGraw Electric Company, Elgin, Ill., a corpora-
tion of Delaware

Application July 17, 1944, Serial No. 545,353

6 Claims. (Cl. 219—39)

1

My invention relates to electric heating and particularly to systems for controlling the energization of the electric heater for a domestic hot water tank.

Among the objects of my invention are the following: to provide a control system for the electric heater of a domestic hot water storage tank that shall cause immediate energization of the heater after closure of the time switch in case the tank contains a predetermined relatively large amount of cold water, said energization continuing until all of the water in the tank is hot, and to cause energization of the heater with a predetermined time period of delay after closure of the time switch in case the tank contains a relatively small amount of cold water, said energization continuing until all of the water in the tank is hot.

Other objects of my invention will either be apparent from a description of one form of control system embodying my invention or will be pointed out in the course of such description and set forth particularly in the appended claims.

In the drawing,

Figure 1 is a vertical, sectional view through a domestic hot water tank, with which is associated the control system embodying my invention, and.

Fig. 2 is a diagram of connections embodying my invention.

Referring first to Fig. 1 of the drawing, I have there illustrated an ordinary domestic hot water tank 11 having a lower cold water inlet pipe 13, an upper hot water outlet pipe 15, a mass 17 of heat-insulating material surrounding the tank 11, which mass is held in proper operative position by an outer casing 19. An electric heater 21, which may be the only heater, and, if so, is preferably located adjacent the bottom end portion of the tank, is provided and may be located in a tunnel member 23. I have illustrated an electric heater 21 of the clamp-on type, and it is to be understood that any other heater usually used under such circumstances may be used instead of the heater 21.

I provide a lower thermally-actuable heater control switch, designated by numeral 25 and comprising a tubular member 27 having a closed inner end and having its open outer end secured in water-tight engagement in an opening in tank 11 adjacent to the lower end of the tank. An expansion rod 29 is provided in the tube 27 and the outer end thereof is adapted to engage with and be disengaged from a block 31 of electric-insulating material, which latter is mounted on

2

the free end of a substantially resilient contact arm 33. This contact arm is adapted to engage with and be disengaged from a substantially rigid contact arm 35, the two contact arms being supported by blocks 37 of electric-insulating material. The design, construction, and adjustment of the thermally-actuable switch 25 is such that when the tube 27 is surrounded by cold water, the length of expansion rod 29 will be a minimum and the two contact arms 33 and 35 will be in electrical engagement with each other. When the tube 27 is subject to hot water, the length of expansion rod 29 will be such that the resilient contact arm 33 will have been moved out of engagement with the rigid contact arm 35. While I have illustrated and described a specific embodiment of a thermally-actuable heater control switch, I do not desire to be limited thereto, since any other form of thermally-actuable switch effective for the same purpose may be used in place thereof.

When I speak of cold water, I mean water, the temperature of which is on the order of 60° to 70° F., and when I speak of hot water, I refer to water, the temperature of which is on the order of 150° F., or slightly higher. The switch will be in closed position when the tube 27 is surrounded by cold water, and the position of the switch 25 in its relation to the electric heater 21 is such that it will be moved to open position when substantially all of the water in the tank is hot.

I provide a thermal retarder heater control switch unit, designated generally by numeral 39, which unit is positioned in heat-receiving relation on the tank at substantially the mid-height thereof. The thermal retarder heater control switch unit 39 is generally disclosed and claimed in my co-pending patent application, S. N. 537,941, filed May 29, 1944, and assigned to the same assignee as is the present application. While the thermal retarder switch unit disclosed and claimed in my above identified co-pending application has only two switch units therein, the present thermal retarder switch unit has three such switches therein, the design of which is similar to those shown in the above identified application.

A first thermal heater control switch comprises a bimetal bar 41, having one end thereof fixed and having a pair of pivot plates 43 secured to the two spaced end portions of the free end thereof. I provide further a second bimetal bar 45, having two sharpened ends adapted to pivotally engage depressions in the pivot plates 43 and to be held in operative position therein by

an over center spring 47, which is located in two aligned central longitudinally extending slots in the two bimetal bars 41 and 45, which will cause the free end of bar 45 to move with a snap action upon change of temperature. A contact bridging member 49 is insulatedly mounted on the free end of the second bimetal bar 45 and is adapted to engage with and be disengaged from a pair of fixed contact members 51 and 53. The design, construction, and adjustment of the first thermal switch, comprising the bimetal bars 41 and 45, is such that the contact bridging member 49 will be in engagement with the fixed contacts 51 and 53 when the temperature of the bimetal bars is on the order of 60 to 70° F., that is when the thermal retarder switch unit is subject to cold water in the tank. When the thermal retarder switch unit is subject to hot water in the tank, the contact bridging member 49 will be out of engagement with the contacts 51 and 53 and bimetal bar 45 will engage a stop 54.

I provide a second thermally-actuable switch, comprising a bimetal bar 55, having one end thereof fixedly secured and having a pair of pivot plates 57 secured to the two spaced end portions of the bar. A second bimetal bar 59, with a pair of sharpened inner end portions fitting into the pivot plates 57, is held in proper operative position as by an over center spring 61 positioned in two aligned central longitudinally-extending slots in the two bars 55 and 59, which will cause movement of the free end of bimetal bar 59 with a snap action upon change of temperature. A contact bridging member 63, insulatedly mounted on the free end of the second bimetal bar 59, is adapted to engage with and be disengaged from a pair of fixed contact members 65 and 67. The first bimetal bar 55 of the second thermal switch is provided with a low-wattage heating coil 69 insulatedly mounted on and around the bimetal bar 55. The design, construction, and adjustment of the second thermal switch, comprising the bimetal bars 55 and 59, is such that the contact bridging member 63 will be out of engagement with contacts 65 and 67 at temperatures up to values on the order of 200° to 250° F. and will be in engagement with the contact members at temperatures above those values. When the second thermal switch is open, the bimetal bar 59 will be in engagement with a stop 70.

The thermal retarder switch unit includes a third switch, comprising a first bimetal bar 71, having one end thereof fixed and having a pair of pivot plates 73 secured to the two spaced end portions thereof. A second bimetal bar 75, with sharpened inner end portions, is adapted to be held in pivotal engagement with the pivot plates 73 by an over center spring 77, which latter is positioned in two central longitudinally-extending slots in the adjacent ends of bimetal bars 71 and 75, so that movement of the free end of bimetal bar 75 will take place with a snap action upon change of temperature. A contact bridging member 79 is mounted on the outer end of the second bimetal bar 75 and is adapted to engage with and be disengaged from two fixed contact members 81 and 83. I provide further a heating coil 85, which is insulatedly mounted on the first bimetal bar 71 and which, while the amount of energy translated into heat therein is relatively small, is so designed and constructed as to be traversed by the same current as traverses the heater 21, as will be hereinafter set forth in detail. When the third thermal switch is open, the bimetal bar 75 will engage a stop 86. The design,

construction, and adjustment of the third thermal switch is such that it will be in open position at all temperatures below 200° to 250° F., but will be in closed position at all temperatures above that. The energy translated into heat in heating coil 85 is such that bimetal bar 75 will have its temperature raised to 200° to 250° F. in from fifteen to thirty minutes when traversed by the heater current.

10 I provide further a time-controlled switch, comprising two contact arms 87 and 89, which are adapted to be out of engagement with each other during on-peak periods of a twenty-four hour day but are adapted to be held in engaged position with each other during off-peak periods of a twenty-four hour day by a continuously operative timer.

I provide two supply circuit conductors 91 and 93, supply circuit conductor 91 being connected to the first contact arm 87 of the time-controlled switch. Contact arm 89 of the time-controlled switch is connected by a conductor 95 with fixed contact member 53. A conductor 97 connects the two fixed contacts 51 and 81. A conductor 99 connects the conductor 97 to one terminal of the heater 85 of the third thermal switch and also connects conductor 97 to contact 65 of the second thermal switch. The contact 67 is connected by a conductor 101 with the second contact arm 89 of the time-controlled switch. A conductor 103 connects contact 67 with one terminal of heating coil 69 on bimetal bar 55, the other terminal of this heating coil being connected by a conductor 105 to contact arm 35 of the lower thermally-actuable switch 25. Contact arm 35 is connected by a conductor 107 to one terminal of heater 21, the other terminal of which is connected by a conductor 109 to the other terminal of heating coil 85 on bimetal bar 71. Contact 83 of the third thermal switch is connected by a conductor 111 to the first contact arm 87 of the time-controlled switch. Contact arm 33 of the lower thermally-actuable switch is connected by a conductor 113 to the second supply circuit conductor 93.

Let it be assumed that a relatively large amount of hot water has been withdrawn from the tank during say daylight or on-peak hours, the amount of water thus withdrawn being sufficient to cause the thermal retarder switch unit to be subject to cold water. This will cause snap-acting movement of the contact bridging member 49 into engagement with the fixed contacts 51 and 53. The lower thermally-actuable switch 25 will, of course, also be in closed position, since it also will be subject to cold water. However, since the off-peak period has not yet been reached, no energization of the control circuit will be effected. Let it now be assumed that the contact arm 87 is moved into engagement with contact arm 89, which will occur upon starting of an off-peak period, which, for illustrative purposes, may be considered to begin at say 10 p. m. or 11 p. m. This will cause an energizing circuit to be closed through the heater, traceable as follows: 60 from supply circuit conductor 91 through engaged arms 87 and 89, through conductor 95, through the engaged contact bridging member 49 and contacts 53 and 51, through conductors 97 and 99, through the heating coil 85 on the third thermal switch, through conductor 109, heater 21, conductor 107, through the engaged contact arms 35 and 33, and through the conductor 113 to the second supply circuit conductor 93. The design, construction, and adjustment of the heating coil 85 on the bimetal bar 71 of the third

thermal switch is such that the temperature rise of particularly bimetal bar 71 will be such that within say fifteen or thirty minutes the contact bridging member 79 will be moved with a snap action into engagement with contacts 83 and 81, whereby a new energizing circuit is closed through heater 21, this circuit being traceable as follows: from supply circuit conductor 91 through conductor 111, engaged contact bridging member 79 and contacts 83 and 81, conductors 97 and 99, through heating coil 85, through conductor 109, heater 21, conductor 107, through the engaged contact arms 35 and 33, and through conductor 113 to the second supply circuit conductor 93.

This energization will continue, irrespective of the position of the two contact arms 87 and 89 of the time-controlled switch, until substantially all of the water in the tank is hot, when de-energization of the heater 21 will be effected by the lower thermally-actuable switch 25. Thus, if for some reason an additional amount of hot water was withdrawn from the tank during the late night hours, so that the thermal retarder was again subject to cold water, the energization of the heater 21 would continue, irrespective of termination of the off-peak period and opening of the time-controlled switch, until substantially all of the water in the tank was hot.

Let it now be assumed that only a relatively small amount of hot water was withdrawn from the tank during daylight hours, so that only the lower thermally-actuable switch 25 is subject to cold water, with attendant closure of switch 25. No energizing circuit would be closed until after closure of the time-controlled switch. The first thermal switch of the thermal retarder switch unit would be in open position, since the thermal retarder switch unit would be subject to hot water, and the second and third thermal switches of the thermal retarder switch unit would also be in open position.

As soon as contact arm 87 is moved into engagement with contact arm 89 by the time-controlled switch at the start of an off-peak period, an energizing circuit through heating coil 69 would be closed, traceable as follows: from supply circuit conductor 91, through the time-controlled switch contact arms 87 and 89, through conductors 101 and 103, heating coil 69, conductor 105, through the contact arms 35 and 33, and through conductor 113 to the second supply circuit conductor 93. The amount of energy translated into heat in the heating coil 69 is such that the temperature of the bar 55 will be raised to a value on the order of 200° to 250° F. in from four to six hours, and when this temperature has been reached, the contact bridging member 63 will be moved into engagement with contacts 67 and 65 with a snap action to thereby close a heating circuit through the heater 21, which circuit is substantially the same as that first above described upon closure of the time-controlled switch, this continuing until the third thermal switch has had its temperature raised with attendant snap-acting closure of the switch controlled thereby. The energizing circuit through heater 21 will then be as follows: from the first supply circuit conductor 91 through conductor 111, through the engaged contact bridging member 79 and contacts 83 and 81, through conductors 97 and 99, heater 85, conductor 109, heater 21, conductor 107, through the engaged contact arms 35 and 33, and through the conductor 113 to the second supply circuit conductor 93. This energizing circuit for heater 21, as will be noted, is entirely

independent of the time-controlled switch, so that should additional hot water be withdrawn from the tank just before substantially all of the water in the tank is hot, energization of heater 21 will be continued, irrespective of opening of the time-controlled switch, until substantially all of the water in the tank is hot, when the lower thermally-actuable switch 25 will operate to de-energize the heater 21 and the whole system.

The system embodying my invention is therefore effective to selectively cause immediate energization of the heater upon closure of the time-controlled switch, or to cause energization of the heater with a predetermined time delay, in accordance with the amount of cold water in the tank, such energization continuing until substantially all of the water in the tank is hot, irrespective of the possible opening of the time-controlled switch. This will ensure that the tank is substantially full of hot water at the start of the morning on-peak period.

Various modifications may be made in the system embodying my invention without departing from the spirit and scope thereof, and all such modifications coming clearly within the scope of the appended claims shall be considered as covered thereby.

I claim as my invention:

1. A system for controlling the energization of an electric heater operatively associated with a domestic hot water tank subject to withdrawal of hot water during a twenty-four hour day, comprising an electric heater, a lower thermally-actuable heater control switch mounted in heat-receiving relation on the tank adjacent to the lower end thereof and adapted to be in closed position when subject to cold water in the tank and to be in open position when subject to hot water in the tank, a time-controlled switch adapted to be in closed position during off-peak periods only, a three-switch thermal retarder heater control unit mounted in heat-receiving relation on the tank intermediate the ends thereof, comprising a first thermal switch adapted to be in closed position when subject to cold water in the tank and in open position when subject to hot water in the tank, a second thermal switch adapted to be in open position when subject to cold and to hot water in the tank and to be in closed position when subject to a predetermined appreciably higher temperature, a heating coil for raising the temperature of said second switch to said predetermined temperature, the energization of said heating coil being controlled jointly by said lower and said time-controlled switches, a third thermal switch adapted to be in open position when subject to cold and to hot water in the tank and to be in closed position when heated to a predetermined appreciably higher temperature, and a heating coil for said third switch adapted to be transversed by the heater current and other electric connections between said electric heater and said switches to cause immediate energization of said heater upon closure of said time-controlled switch in case said first thermal switch of the thermal retarder unit is subject to cold water in the tank.

2. A system for controlling the energization of an electric heater operatively associated with a domestic hot water tank subject to withdrawal of hot water during a twenty-four hour day, comprising an electric heater, a lower thermally-actuable heater control switch mounted in heat-receiving relation on the tank adjacent to the

lower end thereof and adapted to be in closed position when subject to cold water in the tank and to be in open position when subject to hot water in the tank, a time-controlled switch adapted to be in closed position during off-peak periods only, a three-switch thermal retarder heater control unit mounted in heat-receiving relation on the tank intermediate the ends thereof, comprising a first thermal switch adapted to be in closed position when subject to cold water in the tank and in open position when subject to hot water in the tank, a second thermal switch adapted to be in open position when subject to cold and to hot water in the tank and to be in closed position when subject to a predetermined appreciably higher temperature, a heating coil for raising the temperature of said second switch to said predetermined temperature, the energization of said heating coil being controlled jointly by said lower and said time-controlled switches, a third thermal switch adapted to be in open position when subject to cold and to hot water in the tank and to be in closed position when heated to a predetermined appreciably higher temperature, and a heating coil for said third switch adapted to be traversed by the heater current and other electric connections between said electric heater and said switches to cause immediate energization of said heater upon closure of said time-controlled switch through said lower thermally-actuable switch and said first thermal switch.

3. A system for controlling the energization of an electric heater operatively associated with a domestic hot water tank subject to withdrawal of hot water during a twenty-four hour day, comprising an electric heater, a lower thermally-actuable heater control switch mounted in heat-receiving relation on the tank adjacent to the lower end thereof and adapted to be in closed position when subject to cold water in the tank and to be in open position when subject to hot water in the tank, a time-controlled switch adapted to be in closed position during off-peak periods only, a three-switch thermal retarder heater control unit mounted in heat-receiving relation on the tank intermediate the ends thereof, comprising a first thermal switch adapted to be in closed position when subject to cold water in the tank and in open position when subject to hot water in the tank, a second thermal switch adapted to be in open position when subject to cold and to hot water in the tank and to be in closed position when subject to a predetermined appreciably higher temperature, a heating coil for raising the temperature of said second switch to said predetermined temperature, the energization of said heating coil being controlled jointly by said lower and said time-controlled switches, a third thermal switch adapted to be in open position when subject to cold and to hot water in the tank and to be in closed position when heated to a predetermined appreciably higher temperature, a heating coil for said third switch adapted to be traversed by the heater current and other electric connections between said electric heater and said switches to cause immediate energization of said heater upon closure of said time-controlled switch through said lower thermally-actuable switch and said first thermal switch, said energization continuing through said lower thermally-actuable switch and said third thermal switch of the thermal retarder unit until substantially all of the water in the tank is hot.

4. A system for controlling the energization of

an electric heater operatively associated with a domestic hot water tank subject to withdrawal of hot water during a twenty-four hour day, comprising an electric heater, a lower thermally-actuable heater control switch mounted in heat-receiving relation on the tank adjacent to the lower end thereof and adapted to be in closed position when subject to cold water in the tank and to be in open position when subject to hot water in the tank, a time-controlled switch adapted to be in closed position during off-peak periods only, a three-switch thermal retarder heater control unit mounted in heat-receiving relation on the tank intermediate the ends thereof, comprising a first thermal switch adapted to be in closed position when subject to cold water in the tank and in open position when subject to hot water in the tank, a second thermal switch adapted to be in open position when subject to cold and to hot water in the tank and to be in closed position when subject to a predetermined appreciably higher temperature, a heating coil for raising the temperature of said second switch to said predetermined temperature, the energization of said heating coil being controlled jointly by said lower and said time-controlled switches, a third thermal switch adapted to be in open position when subject to cold and to hot water in the tank and to be in closed position when heated to a predetermined appreciably higher temperature, and a heating coil for said third switch adapted to be traversed by the heater current and other electric connections between said electric heater and said switches to cause immediate energization of said heater upon closure of said time-controlled switch through said lower thermally-actuable switch and said first thermal switch, said energization continuing through said lower thermally-actuable switch and said third thermal switch of the thermal retarder unit until substantially all of the water in the tank is hot, deenergization of the heater being then effected by said lower thermally-actuable switch.

5. A system for controlling the energization of an electric heater operatively associated with a domestic hot water tank subject to withdrawal of hot water during a twenty-four hour day, comprising an electric heater, a lower thermally-actuable heater control switch mounted in heat-receiving relation on the tank adjacent to the lower end thereof and adapted to be in closed position when subject to cold water in the tank and to be in open position when subject to hot water in the tank, a time-controlled switch adapted to be in closed position during off-peak periods only, a three-switch thermal retarder heater control unit mounted in heat-receiving relation on the tank intermediate the ends thereof, comprising a first thermal switch adapted to be in closed position when subject to cold water in the tank and in open position when subject to hot water in the tank, a second thermal switch adapted to be in open position when subject to cold and to hot water in the tank and to be in closed position when subject to a predetermined appreciably higher temperature, a heating coil for raising the temperature of said second switch to said predetermined temperature, the energization of said heating coil being controlled jointly by said lower and said time-controlled switches, a third thermal switch adapted to be in open position when subject to cold and to hot water in the tank and to be in closed position when heated to a predetermined appreciably higher temperature, a heating coil for said third switch adapted to be traversed by the heater current and other electric connections between said electric heater and said switches to cause immediate energization of said heater upon closure of said time-controlled switch through said lower thermally-actuable switch and said first thermal switch, said energization continuing through said lower thermally-actuable switch and said third thermal switch of the thermal retarder unit until substantially all of the water in the tank is hot, deenergization of the heater being then effected by said lower thermally-actuable switch.

adapted to be traversed by the heater current and other electric connections between said electric heater and said switches to selectively cause energization of said heater immediately upon closure of said time-controlled switch in case said thermal retarder unit is subject to cold water in the tank and with a predetermined time delay period after closure of said time-controlled switch in case only the lower thermally-actuable switch is subject to cold water at the time of closure of said time-controlled switch.

6. A system for controlling the energization of an electric heater operatively associated with a domestic hot water tank subject to withdrawal of hot water during a twenty-four hour day, comprising an electric heater, a lower thermally-actuable heater control switch mounted in heat-receiving relation on the tank adjacent to the lower end thereof and adapted to be in closed position when subject to cold water in the tank and to be in open position when subject to hot water in the tank, a time-controlled switch adapted to be in closed position during off-peak periods only, a three-switch thermal retarder heater control unit mounted in heat-receiving relation on the tank intermediate the ends thereof, comprising a first thermal switch adapted to be in closed position when subject to cold water in the tank and in open position when subject

to hot water in the tank, a second thermal switch adapted to be in open position when subject to cold and to hot water in the tank and to be in closed position when subject to a predetermined appreciably higher temperature, a heating coil for raising the temperature of said second switch to said predetermined temperature, the energization of said heating coil being controlled jointly by said lower and said time-controlled switches, a third thermal switch adapted to be in open position when subject to cold and to hot water in the tank and to be in closed position when heated to a predetermined appreciably higher temperature, a heating coil for said third switch adapted to be traversed by the heater current and other electric connections between said electric heater and said switches to selectively cause energization of said heater immediately upon closure of said time-controlled switch in case said thermal retarder unit is subject to cold water in the tank and with a predetermined time delay period after closure of said time-controlled switch in case only the lower thermally-actuable switch is subject to cold water at the time of closure of said time-controlled switch, said heater being deenergized by said lower thermally-actuable switch when substantially all of the water in the tank is hot.

CLARK M. OSTERHELD.
